UNITED STATES PATENT OFFICE.

WALTER R. ATKESON, OF TACOMA, WASHINGTON.

INTERNAL-COMBUSTION ENGINE.

Application filed April 18, 1927. Serial No. 184,741.

This invention relates to internal combustion engines and especially to that class of such engines wherein the cylinders are parallel to and surround the engine shaft.

5 The objects of this invention are to increase the efficiency of such engines; to decrease vibrations; and to decrease the cost of manufacture.

I attain the increase in efficiency by means 10 of the long stroke and small bore of the cylinder with the resulting high piston speed: also the peculiar relations between the pistons and shaft result in a relatively low shaft speed. The efficiency is further increased by 15 the fact that the peripheral speed of the rotor is high and the friction loss thereon is low; and also by the peculiar valve motion which is equivalent to a substantial increase in the diameter of the valve. The decrease in vibration of the machine is attained by the static balance of all moving parts in all positions, and by the substantial dynamic balance thereof. The decrease in the cost of 20 manufacturing of the machine is attained by 25 the reduction of moving parts thereof as well as by the duplication of parts throughout the machine, there being no right- and left-hand construction therein.

Other objects are, first, to reduce the wear 30 of the cylinders by removing all torque therefrom; second, to eliminate spur gears for driving the valve operating apparatus; third, to provide a special mechanism for operating the valves whereby they are given an intermittent motion, being opened and closed 35 suddenly and being held open a substantial time instead of opening and closing with a substantially continuous movement as usually constructed under present practice, thereby 40 diminishing the throttling action of the valves on the flowing gases and producing an effect equivalent to a much larger valve; fourth, to operate, with consecutive action, 45 all parts of the cycles in each cylinder in each end of the machine; fifth, to reduce the weight per horse power of such an engine and especially to reduce the weight of its reciprocating parts; sixth, to reduce shock and vibration in the machine by the special 50 form of the rotor cam grooves, said grooves being formed with their center lines on reversed parabolas whereby uniform acceleration and retardation of the pistons is attained; and seventh, to reduce the friction 55 between each piston and the rotor and to nar-

row down the rotor whereby its wearing qualities are increased.

In the particular form of engine illustrated and described herein eight cylinders are mounted in four opposed pairs, which arrangement results in eight power-strokes to the cycle of two revolutions of the shaft, each power-stroke applying its power through substantially two right angles thereby making 1440 degrees of power-stroke in 720 degrees of revolution and thereby giving a practically constant torque throughout the whole revolution.

I attain these and other objects by the devices, mechanisms, and arrangements illustrated in the accompanying drawings in which:

Fig. 1 is a plan view of my engine as viewed on a line lying at 45 degrees from the vertical, and showing a part thereof broken away 75 and in section to reveal the interior thereof; Fig. 2 is an elevation of the engine shaft and rotor; Fig. 3 is a section of the shaft on the line 2—3 in Fig. 2 showing the duplex cam-operating wheels which control the motion of 80 the intake valve cam; Fig. 4 is a similar view on the line 4—4 in Fig. 2 showing the duplex cam-operating wheels which control the motion of the exhaust valve cam; Fig. 5 is a plan view of the machine showing a part thereof 85 in section and showing a portion of one end thereof removed from the frame; Fig. 6 is a diagrammatic illustration showing the positions of the four double pistons in successive quarter-turns in two revolutions of the shaft; 90 Figs. 7 and 8 are simultaneous diagrams of the successive states of the gas in the two cylinders at opposite ends of any double piston, taken in the directions indicated by the arrows thereon; Fig. 9 is an end elevation of my 95 improved engine, showing the valve mechanism of one of the cylinders, in section; Fig. 10 is a section on the line 10—10 in Fig. 5; Fig. 11 is a section on the line 11—11 in Fig. 5; Fig. 12 is a view of the development of the 100 cam surface of the rotor showing simultaneous positions of the four double pistons; Fig. 13 is an elevation of one of the double pistons as viewed from the engine shaft; Figs. 14, 15, and 16 are sections of the said double 105 piston taken respectively on the lines 14—14, 15—15, and 16—16, in Fig. 13; Fig. 17 is a longitudinal section of either valve cam apparatus, demounted from the engine shaft; Figs. 18 and 19 are cross sections thereof 110

taken on the lines 18—18, and 19—19, in Fig. 17 respectively; Figs. 20, 21, 22, and 23 are perspective views showing the valve cam mechanism in four successive positions which are separated by two right angles.

Similar numerals of reference refer to similar parts throughout the several views.

The frame of my improved engine comprises a central cylindrical drum 1 having two opposite supporting arms 2, extending from its sides, by means of which it is attached to the engine support. The drum 1 is provided with circular flanges 3, on each end. Two frame plates 4 close the ends of the drum 1 and are secured to the said flanges 3, and each is provided with a central bearing 5 for the engine shaft.

Four engine cylinders are mounted on each of the said frame plates 4, those on the one hand being in axial alinement with those on the other hand, all of the said cylinders being symmetrically arranged about the central axis of the engine and equidistant therefrom. Each of the said pairs of cylinders contains one double piston which extends across the inside of the drum 1 and which engages the cam grooves of the rotor mounted within the drum. All of the cylinders on one end of the machine have their valves controlled by a single pair of valve cam actuating wheels and therefore each cylinder in succession passes through each phase of the cycle. It will therefore be understood that in the herein description of one cylinder, or one pair of cylinders, or of one set of cylinders, that the description equally applies to the other cylinders or pairs of cylinders, or set of cylinders.

The shaft 6 passes centrally through the machine from end to end, and is supported therein in the central bearings 5 as well as in the hereinafter described apparatus for operating the valves, positioned at both ends of the engine. The shaft 6 has the rotor 7 mounted on its center between the plates 4 of the frame and between the bearings 5, and is provided with similar valve cam-sleeves 8 at each end.

Referring particularly to Fig. 12, which shows the developed surface of the rotor 7 with the pistons laid thereon, the outer cylindrical surface of the rotor 7 is grooved forming threads between the grooves 9. The guide curve used in laying out the grooves 9 consists of two parabolas laid upon the surface of the rotor 7 and tangent at the ends of their latusrecta, said latusrecta lying in a plane normal to the axis of the rotor. The grooves are equidistant from each other and parallel. The layout curve may be the center line of the groove, if desired, but not necessarily, the essential feature being that such groove consists of two or more parabolas tangent to straight lines connecting them. This layout is intended to cover a case where a layout curve so composed of two or more

straight lines connecting them, that is, a straight portion might be inserted between the parabolas, which arrangement might be desirable under certain conditions. As a result of this form of the grooves 9 the positive and negative accelerations of the reciprocating pistons, which engage the said grooves 9, as hereinafter described, are uniform, thus eliminating longitudinal shock in the machine.

The cylinders 10 extend out from the plate 4, at right angles thereto, and are provided with suitable heads 11 and are secured to the said plate 4 by means of bolts 12 in the usual way. Each cylinder is surrounded by a suitable jacket 13 clamped between the plate 4 and an outer plate 14, adjacent the said head 11, thereby forming a water chamber around the cylinder.

Referring particularly to Figs. 1 and 13 it will be seen that the double piston 15, which reciprocates in the two opposite aligned cylinders 10, is provided at each end with suitable piston rings in the usual manner and that the portion between the said ends is of special shape. The length of the piston from end to end is slightly greater than the length of one cylinder 10 together with the width of rotor 7. The part immediately adjacent the piston ends is especially illustrated in Fig. 14 and is hollow and its outer surface is cylindrical except for a short concave portion. In general the shape of the central part of the double piston 15 is semicylindrical, but it is lightened by means of cavities 16, and is shown particularly in Fig. 15. The surfaces terminating the semicylindrical portion are curved on the radius of the rotor 7 and form shoulders 17 which bear thereon and which prevent the piston from rotating in the cylinder under the torque strain produced by the rotor. Five lugs or fingers 18 project inward from the above described semicylindrical body, between the above cavities 16, and each comprises a substantially diamond-shaped figure having its two central corners rounded, Figs. 12 and 13. The section of these fingers is particularly illustrated in Fig. 16. The fingers are preferably provided with a central hole for the purpose of lightening them.

The distance between the centers of the fingers 18 is exactly equal to the distance between the centers of the above described grooves 9 in the rotor 7 in a line parallel with the shaft. Thus it will be seen that when the piston 15 moves in the cylinders 10 it applies a longitudinal pressure to the rotor and, since the walls of the grooves 9 are at an angle to the direction of motion of the piston 15 and fingers 18, it follows that such motion of the piston induces a lateral and therefore rotary motion to the rotor 7. As clearly seen in the drawings, three fingers 18 are always in contact with the walls of the grooves 9 and thus it is possible to have the stroke of the piston

considerably longer than width of the rotor 7. As above stated, the said fingers 18 are substantially diamond-shaped, being formed of two diagonally opposite pairs of straight portions 19, making a right angle to each other; said pairs being joined by rounded portions 20, made on the radius of half the distance between the opposite ends of such straight portions 19. Therefore, by referring to Fig. 12, it will be seen that during any stroke of the piston the force of the piston is transmitted along a contact line on said curved surface 20, and groove 9; said contact line rocks back and forth from one straight surface 19 to the other and back again, thereby reducing the wear on the grooves 9 and the fingers 18.

Each cylinder 10 is provided with a head 11 containing a combustion chamber 21 which lies substantially at right angles to the radial line from the shaft to the cylinder, as shown in the upper right hand corner of Fig. 9. Each combustion chamber 21 is provided with an intake valve 22 controlling the intake passage 23, and with an exhaust valve 24 controlling the exhaust passage 25. The valves 22 and 24 are side by side as clearly shown in Fig. 9. A spark plug 26 is screwed into the combustion chamber 21 immediately adjacent to the intake valve 22. The valves 22 and 24 are of the usual form for such engines and are closed under the action of helical valve springs 27, surrounding the valve stems 28, and are opened by the motion of the respective valve cams, herein-after described, one such cam being provided for each valve as clearly shown in Fig. 9.

On each end of the shaft 6, at a point in line with the valve stems 28, of all the valves 22 and 24 are mounted duplicate valve-operating devices. These devices are set lying in the same direction on the shaft 6 but that on one end is rotated 180 degrees from that on the other end of the shaft. Each comprises a sleeve 8, secured on the shaft 6 by a suitable key 29 and two pairs of complementary or duplex cam-operating wheels mounted on the ends of the said sleeve 8. The two duplex cam-operating wheels 30 and 31 at the left end of the sleeve form the mechanism for actuating the intake valve cam 32 while the two duplex cam-operating wheels 33 and 34 at the right end of the sleeve form the actuating mechanism for the exhaust valve cam 35. As shown, particularly in Figs. 1, 5, and 17, the intake valve cam 32 and the exhaust valve cam 35 are mounted between the central walls 36 of the duplex cam box and one pair of cam-operating wheels 30 and 31 lie in one end of said box while the other pair of cam-operating wheels 33 and 34 lie in the other end of the box. One said central wall 36, adjacent to the outer frame plate 14, is square (Fig. 9) and is attached to said plate 14 by bolts at its cor-

ners (Figs. 5 and 9). The valve cams 32 and 35 are identical for all the valves in the engine. The valve cams are perhaps best illustrated in Figs. 17 to 23 and each comprise a shank 37, one end of which lies in one of the above-mentioned inner walls 36 and the other end of which passes through the other said inner wall 36 and projects over the cam-actuating wheels in one or the other end of the cam box, (see Fig. 17). The valve cam 32 or 35 extends from the shank 37 and lies between the said inner walls 36 as above noted. That part of the shank 37 which lies over the cam-actuating wheels is provided with two double complementary lugs or teeth 38 and 39 said lugs being set at right angles to each other and extending on both sides of the said shank 37. The teeth 38 operate to open the valve and the teeth 39 operate to close it. The duplex cam-actuating wheels 30 and 31, which control the intake valve cam 32 each comprise, in essence, a one-toothed wheel or a wheel having two unequal radii, the tooth or long radius of the one wheel being opposite to the short radius of the other wheel and the step or impact face of one tooth being in alinement with the step or impact face of the other wheel. The two said steps of each wheel are separated by the number of degrees which it is desired that the intake valve 22 may be opened or closed, as the case may be. The cam-operating wheel 30 engages the teeth 38 of the shank 37 while the complementary wheel 32 engages the teeth 39 thereof.

Similarly, the duplex cam-actuating wheels 33 and 34, which control the exhaust valve cam 35, are similar to the above described cam-actuating wheels 30 and 31 except that the distance between the steps or impact faces therein, which govern the points at which the exhaust valve 24 is opened and closed, are different from the corresponding points in the wheels 30 and 31. Also the mounting of the sets of wheels on the sleeve 29 is different, the one from the other, as clearly shown in Figs. 18 to 23.

In Figs. 20 to 23, inclusive, I have shown the two sets of duplex cam-actuating wheels in several successive positions (180° apart) together with one pair of valve operating devices comprising the shanks 37 with the cams 31 and 35 and the above-described lugs or teeth 38 and 39. In Fig. 20 the position of the shaft 6 is such that it has turned between ten and fifteen degrees beyond the vertical, as shown in Figs. 7 and 8, at which time the engine has just completed exhausting the burned gases, the exhaust valve 24 has just closed, and the intake valve 22 is being opened. The exhaust valve cam 35 has been turned to close the exhaust valve 24 and lies in a substantially tangential direction relatively to the center of the shaft 6, and is stationary, and the intake valve cam 32 is be-

ing turned to open the intake valve 22. The said cam 32 is being turned because the approaching impact face of the cam-operating wheel 30 is engaging one of the teeth 38, 5 which has been radial from the center of the shaft 6 previous to this moment, to turn the shank 37, and, simultaneously, one of the teeth 39 which has been tangential and in sliding contact with the cam-operating wheel 10 31, is turning and sliding down the retreating step or impact face of the said wheel 31. This represents the position of the valves when the piston is drawing the explosive mixture into the cylinder controlled thereby. 15 In Fig. 21 the shaft 6 has turned through 180° and therefore is from ten to fifteen degrees beyond the vertical as shown in Figs. 7 and 8. In this position the exhaust valve cam 35 has again been actuated by the impact face of the cam-operating wheel 33 20 engaging one of the teeth 38 to turn the shank 37 so that both the teeth 38 lie tangential to the center of the shaft and said valve cam 35 is pointed inward, substantially 25 parallel with the axis of the valve stem, and simultaneously the intake valve cam 32 has been turned down at right angles to its valve-opening position and, therefore, the said intake valve 22 has been closed, the impact face 30 of the cam operating wheel 31 having engaged the tooth 39 to turn the shank 37 and to bring both teeth 39 into tangential position relatively to the center of the shaft 6. This represents the position of the valves 35 when the piston is compressing the gases in the cylinder. In Fig. 22 the shaft 6 has again turned through two right angles and occupies the same position that it does in Fig. 20, but the two valve cams 32 and 35 40 are each in positions opposite to those illustrated in Fig. 20. In this case both of the valves 22 and 24 controlled by the cams 32 and 35 are still closed. This represents the position of the parts during the firing stroke 45 of the piston. In Fig. 23 the shaft 6 has again turned through two right angles and the cam-operating wheels occupy the same positions as illustrated in Fig. 21. In this case the exhaust valve cam 35 has just been 50 turned to point outward to open the said exhaust valve 24, while the intake valve cam 32 has also been turned through a right angle but the intake valve 22 remains closed. This represents the position of the parts 55 during the exhaust stroke of the piston.

It will be observed from the drawings, especially Figs. 18 to 23, that the teeth 38 and 39, which are mounted on the several shanks 37 are formed with two convex and 60 two concave surfaces. The two convex or end surfaces of the teeth are circular about the center of the said shank 37, while the two concave surfaces which form the sides of the teeth are circular and have an external 65 radius equal to the radius from the center

of the shaft 6 to the outer surface of the several cam operating wheels 30, 31, 33, and 34. The above-mentioned convex surfaces are formed at a radius extending from the center of the shank 37 to, or near to, the 70 inner surface of the said cam-operating wheels, as shown for instance in Fig. 19. When these teeth 38 and 39 occupy their radial positions they are inactive but are adapted to be engaged by the approaching impact 75 face of the cam-operating wheels, when it reaches it, and the shank 37 is therefore adapted to be turned through one right angle by the said impact face as it passes. When the said tooth however occupies a tangential position it, and its opposite tooth, lie 80 on the outer surface of the cam-operating wheel, and therefore slides thereon. This fact prevents any vibration of the said shank 37 and of the valve cam or of the valve. 85 Each valve cam is therefore locked, in any one of its four positions, during substantially one-half revolution of the shaft 6 and, if the said cam has raised its valve, it then holds that valve open and stationary during 90 substantially one-half of the revolution of the shaft 6.

Thus it will be seen that the several valves are each opened once in two revolutions of the shaft 6 and remains open for about one-half a revolution of the shaft, and that the opening and closing motions of the said valves is very rapid, taking place while the shaft 6 is turning through something like twenty degrees. And also it will be understood that since the said valve is held wide open, and stationary, during the greater part of its opened period, the effectiveness of the opening is very materially increased over those valves which move continuously, from 100 closed to full open and back to closed positions, because the valve itself, in my invention, does not throttle the valve passage during the time that it is supposed to be opening as is the case in such continuously moving valves. It might be thought that the sudden motion of the valves would create vibration and noise when the impact face engages and turns the tooth 38 or 39 but, by 105 properly shaping the said impact faces so 110 that the complementary tooth will slide down one impact fact while the other is being turned, in other words unlocking the shank, from one position simultaneously while it is being moved to its next position, the two said 115 teeth 38 and 39 coact to prevent any vibration of the shank 37 and, by properly shaping the cam 32 or 35 and the valve stem wearing piece 40, engaging the cam, the motion of the valve itself can be arranged to have a uniform positive and negative acceleration.

Thus it will be seen that while the engine shaft 6 is making two complete revolutions each of the valve cam shanks 37 makes four quarter turns and each of these quarter turns 130

is made at a very high rate of speed, while the engine shaft is turning through a very few degrees, and that the said shanks 37 do not turn except when the steps in the cam-
5 actuating wheels engage the teeth 38 or 39 thereon. It will also be seen that the four cylinders on each side of the engine act in consecutive order. As shown in Fig. 6 it is evident that the cylinders marked 1, 2, 3, 4,
10 on one side of the engine fire in that order during one revolution of the shaft while the cylinders marked 7, 8, 5, 6, fire in that order during the second revolution of the shaft.

It will be observed in the several drawings, especially in Figs. 1 and 11, that the central part of each piston travels across the drum 1 in the center of the machine and rides in a groove 41 formed in an enlargement 42 on the inner side of the said drum 1, and it
20 will also be observed, especially from Fig. 15, that that portion of the piston has shoulders 17 formed thereon, as above described, which shoulders are adapted to engage the outer surface or threads of the rotor 7 and
25 which prevent the piston 15 from turning in the cylinder 10 or in the said groove 41. Also, it will be understood from Fig. 11, that the torque, or side pressure of the rotor on the piston, is all taken up in the said
30 groove 41 and is not transmitted to the cylinder 10, and that therefore, the said cylinder is relieved of all torque strain.

It is, of course, understood that thrust bearings 43 are inserted between the engine frame plate 4 and the boss of the said rotor 7 whereby the longitudinal thrust of the piston on the rotor is transmitted to the frame.

In my design proper lubrication is easily accomplished as shown on the large drawing.
40 An oil reservoir may be provided at the lowest point of the engine frame, or in any suitable location; any one of the several successful oil pumps can be geared to the main shaft and pump oil to the piston through the engine frame and through the hollow fingers 18, or roller shafts if rollers are used, and into the grooves between the threads on the rotor where the centrifugal force will throw the oil out and over the whole surface of the
45 rotor. Ample oil will drag into the cylinders with the pistons. The oil surplus will gather on the inside of the engine frame and run down over the thrust bearings and down to the bottom of the engine frame and back to the pump. The valve gear may also be supplied with oil from the same pump.

It will be understood that many changes in detail may be resorted to without departing from the spirit of the invention. For example, the cylinders 10 could readily be made to rotate about the central shaft 6, this being common in the art, and the appended claims are intended to cover any such variations and modifications.

Having therefore described my invention, 65 what I claim is:—

1. In an engine, the combination with a fixed frame; a cylinder mounted thereon; a pair of spring closed poppet valves; a shaft mounted in said frame; a pair of valve cams 70 mounted in said frame, each on an axis parallel with said shaft, each said cam adapted to open one said valve; and two sets of means each interposed between said shaft and one said valve cam, whereby each said valve cam 75 is four times intermittently and independently actuated to turn a quarter revolution for every two revolutions of said shaft, and whereby each said valve is opened once in two revolutions of said shaft. 80

2. In an engine, the combination with a fixed frame; a cylinder mounted thereon; a spring closed poppet valve; a shaft mounted in said frame; a valve cam adapted to open said valve and having a shank mounted in 85 said frame on an axis parallel with said shaft; a pair of two-toothed lugs on the shank of said valve cam, said lugs extending from said shank at right angles to each other; and a pair of one-toothed wheels mounted on 90 said shaft and having their teeth at different points around said shaft and each adapted to engage one said two-toothed lugs, whereby said cam is turned a quarter revolution by each said wheels and a half revolution by both 95 said wheels in one revolution of said shaft.

3. In an engine, the combination with a fixed frame; a cylinder mounted thereon; a spring closed poppet valve; a shaft mounted in said frame; a valve cam adapted to open 100 said valve and having a shank mounted in said frame on an axis parallel with said shaft; a pair of one-toothed wheels mounted on said shaft, the tooth of one being complementary to the tooth of the other, each said tooth on 105 one wheel starting where the tooth on the other wheel ends; and a pair of two-toothed lugs on the shank of said valve cam, said lugs extending from the shank at right angles to each other, each adapted to be actuated by the 110 impact face of the tooth of one said wheel when in its radial or set position as said impact face passes, and to lie on the outer face of said tooth when the other lug is in set position, whereby said valve cam is intermittently actuated and is held in its turned position until again actuated. 115

4. In an engine, a cylinder, a shaft having its axis parallel with the axis of said cylinder and rotatable with reference thereto, a cam 120 block carried by said shaft and having a groove formed therein, the center line of said groove being composed of two reversed parabolic curves, a piston reciprocating in said cylinder and means carried by said piston 125 and engaging said cam groove.

5. In an engine, a cylinder, a drive shaft having its axis parallel with the axis of said

cylinder and rotatable with reference thereto, a cam block carried by said shaft and having a plurality of parallel cam grooves formed in the surface thereof, and a piston reciprocating in said cylinder, said piston having a plurality of spaced finger lugs, a lug engaging at least one wall of each cam groove at all times.

6. In an engine, in combination, a cylinder, a drive shaft having its axis parallel to the axis of said cylinder and rotatable with respect thereto, a valve communicating with said cylinder, and a valve cam shaft having its axis parallel to said shaft and fixed with reference to said cylinder, said shaft being operated by the relative rotation of said shaft with respect to the cylinder.

7. In an engine, in combination, a fixed cylinder, a rotatable drive shaft having its axis parallel to the axis of said cylinder, a valve

communicating with said cylinder, and a 20 valve cam shaft operated by said drive shaft and having its axis fixed and parallel to said drive shaft.

8. In an engine, a cylinder, a rotor shaft having its axis parallel with the axis of said cylinder, and rotatable with reference thereto, a cam block carried by said shaft and having a groove formed therein, the layout curve of said groove comprising two parabolic curves tangent at the ends of their latusrecta, 30 said latusrecta lying in a plane normal to the axis of the rotor shaft, a piston reciprocating in said cylinder, and means carried by said piston and engaging said cam groove whereby axial movement of said piston is transformed into rotary motion of said rotor shaft.

In testimony whereof I affix my signature.

WALTER R. ATKESON.
